UNITED STATES PATENT OFFICE.

LUTHER SADLER AND ROBERT C. GECKLER, OF OAKLAND, CALIFORNIA.

RAILROAD-CROSSING.

1,169,196.

Specification of Letters Patent. Patented Jan. 25, 1916.

Application filed November 9, 1914. Serial No. 871,016.

To all whom it may concern:

Be it known that we, LUTHER SADLER and ROBERT C. GECKLER, citizens of the United States, and residents of Oakland, county of Alameda, and State of California, have invented certain new and useful Improvements in Railroad-Crossings, of which the following is a specification.

The invention relates to railroad crossings at which one railroad track crosses another and is particularly adapted to the use of street railways.

One of the objects of the invention is to provide a crossing for street railways which shall give the car-wheels an unbroken passage thereover.

Another object of the invention is to provide a simple and sturdy construction which possesses small liability to become out of order.

Another object of the invention is to provide crossing mechanism which may be operated by the railway cars only.

The invention possesses other advantageous features which with the foregoing, will be set forth at length in the following description where we shall outline in full that form of the invention which we have selected for illustration in the drawings accompanying and forming part of the present specification.

The novelty of the invention will be included in the claims following said description. From this it will be apparent that we do not limit ourselves to the showing made by said drawings and description as we may adopt variations within the scope of our invention as set forth in said claims.

Referring to said drawings: Figure 1 is a plan view of a four-track crossing, several of the rails being broken away to disclose the operative parts and to reduce the size of the figure. Fig. 2 is a vertical section taken on the line $x-x$ Fig. 1. Fig. 3 is a side view of a portion of a rail showing the operating parts, the turntable or rotatable member being shown in section. Fig. 4 is a cross section of a rail taken on the line A—A Fig. 3. Fig. 5 is a cross section of a rail taken on the line B—B Fig. 3. Fig. 6 is a side view of a portion of a rail and car truck disclosing one manner of actuating

the operating mechanism. Fig. 7 is a plan view of one rail intersection.

In railway crossings as heretofore constructed, a transverse groove or slot must be provided in each rail to allow the flange on the wheel of a car traveling on the crossing rail to pass and this break in the rail thread causes the car to receive a decided jar which not only subjects the car to wear and tear but materially shortens the life of the crossing. To obviate these defects means have been heretofore provided whereby a grooved member is positioned at the intersection of each two rails which is rotatable so that the groove in the member is brought into alignment with the grooves of the abutting rails in a direction corresponding with that of the passing car or train. In the latter construction it frequently happens that vehicles other than the railway cars not only ride over the rail tread, but also ride in the groove, and these vehicles operate the turntables at inopportune moments and result in inconvenience or disaster. In accordance with the present invention we provide a separate longitudinal groove in a portion of the rail, which groove is of such width as to exclude the entry of wheels of vehicles and will only permit the reception of a suitable actuating member secured to the railway car.

In Fig. 1 we have shown a four-track crossing, the rails 2, 3, 4 and 5 extending in one direction and the rails 6, 7, 8, 9 extending in another direction and crossing the first set of rails. The rails 2, 3, form track D; the rails 4, 5, track E; the rails 6, 7, track F and the rails 8, 9, track G.

At the intersection of each two rails, the rails are welded together or a steel casing is formed integral with the rails to reinforce the joint, or as shown in the present instance, the intersecting rails are welded to the steel casing 12. The rails shown are grooved rails, but it is to be understood that the invention is applicable to all types of rails whether or not they are provided with a groove for the flange of the wheel.

Each casing 12 is cylindrical in form and seated therein is a turntable or rotatable member 13, which is provided on its upper surface with a tread portion 14 and a groove

15 through which the flange of the moving wheel passes. One of these turntables is arranged at the intersection of each two rails and the turntables are so arranged that 5 they may be rotated about vertical axes so that the tread and groove thereof will register with the tread and groove portions of either set of rails. That is the turntable may be turned so that the tracks D and E 10 present continuous rails or so that the tracks F and G present continuous rails.

The turntable 13 is provided with a centrally located shank 16 projecting downwardly therefrom and at the lower extremity of which is secured a circular plate 17 arranged to overlie the bottom of the casing so that any foreign matter which gains entrance to the interior of the casing falls on the plate and is discharged over the 20 periphery thereof. The dirt finds a ready exit through one or more downward sloping apertures 18 provided at the bottom of the casing.

The interior of the under portion of the 25 shank is recessed so that a ball 19 may be interposed between the upper portion of the recess and the post 21 extending upward from the bottom of the casing. As the ball and bearing surface are completely inclosed 30 by the shank and occur above the plane of the plate 17, it is difficult for any foreign matter to come in contact with the bearing.

The shank 16 is preferably square in cross section and secured thereto is the gear or 35 pinion 22. The turntables 13 are rotated by means of reciprocating rods 23 provided with rack teeth portions 24 engaging the pinions 22.

The groove 15 in the turntable is disposed 40 so that the inner edge thereof is spaced from the center of the turntable, and that portion of the surface of the turntable which constitutes the tread and with which the wheel of the car engages constitutes a diameter of 45 the turntable. In this construction the weight of the car comes on the center line of the turntable and therefore the turntable is not subjected to the bending strain that would occur if the groove was in the center 50 and the tread portion to one side. On account of this construction of the turntables, that is, that the groove is not diametrically placed, the successive turntables must be rotated in opposite directions, in order that 55 the groove and tread portions thereof will become alined with the groove and tread portions of the rails. To accomplish this opposite rotation of the successive turntables, the rack rods are formed so that they 60 mesh on opposite sides of the pinions on the successive turntables. This may be accomplished by bending the rack rod and forming the successive racks on opposite sides thereof.

65 In one rail of each track at a suitable dis-

tance from the intersection of the rails the upper portion of the rail is increased in width preferably on the side adjacent the groove 25 and a separate longitudinal groove 26, is formed therein. The groove is not 70 necessarily formed integral with the rail, but such construction is believed to be preferable. The groove 26 is narrower in cross section than the groove 25 so that the wheel of a horse drawn or other vehicle may 75 not enter the groove.

The groove 26 is provided with an aperture 27 into which the vertically movable plunger 28 extends. The plunger is preferably bent at its upper portion to conform with 80 the shape of the rail and is provided with a cam face 29 at its upper end to insure ready depression by contact with an actuating member. The plunger 28 is also provided with a projection or tooth 31, which is engaged by the bifurcated end of a lever 33, fulcrumed at 34 to the web of the rail. The other end of the lever 33 is attached to the link 36 which is in turn connected to the lug 37 on the rack bar. The depression of 90 the plunger 28 causes the rack bar to move longitudinally and rotate the turntable.

In order to insure the movement of the rack bar through its complete movement so that the turntables will be moved to cause 95 the tread portions thereon to become alined with the tread portions of the rails we provide the lever 38 fulcrumed to the web of the rail at 39, and having its lower arm 41 pivotally secured to the link 36 and the free 100 arm 42 thereof being provided at its upper extremity with a transverse raceway 43, adapted to contain the ball 44. In operation the plunger is depressed whereby the rod 23 and link 36 are caused to move in 105 the proper direction. As the arm 41 of the lever 38 is connected to the said link the movement of the link causes the arm 41 to move therewith and when more than one-half of the throw is completed the raceway 110 43 becomes inclined, causing the ball 44 to roll toward the opposite extremity thereof, shifting the weight thereto and causing the lower arm of the lever and consequently the link 36 and rod 23 to continue the movement in the proper direction to produce the 115 alinement of the grooves.

The reciprocating rods 23 are provided with a plurality of rack portions 24 engaging the pinions 22. A plunger is arranged 120 in one rail of each track and means are provided for interconnecting all of the turntables, so that the depression of one plunger causes all of the turntables in the crossing to move at the same time. Each rod 23 engages all of the turntables in that rail and on account of the intersecting of rails, all of the turntables are operated by the depression of any one plunger.

In the present embodiment of the inven- 125

tion we also provide at a suitable distance beyond the crossing, a second plunger 28^a which when depressed operates to throw the turntables in the proper position for the 5 cars passing in a transverse direction. Assuming that a car approaches the crossing along track (E) the plunger if it is in its upper position will be depressed upon contact with the actuating member on the car, 10 thereby moving all of the turntables to present continuous rails in tracks (D) and (E). The second plunger is arranged to be in its upper position when the first plunger is depressed and as soon as the car has passed 15 over the second plunger and has depressed the same the turntables present continuous rails to the transverse tracks F and G.

Any suitable means may be provided for depressing the plunger. In the present case 20 we have shown a lever 48 pivotally secured to car truck at 49. The upper end of the lever reaches up into the car where it is controlled by the operator. At the lower end of the lever is arranged a roller 51 which is 25 movable into the groove 26, and this roller is preferably located in the vertical plane passing through an axle of the car so that the roller will not be shifted laterally with respect to the rail when the rail is curved. 30 Under certain conditions it is often desirable that the operator on the car may be warned as to the position of the turntables, while at a distance therefrom in order that the car or train may be brought to a stand- 35 still before crossing the tracks if necessary. In this case the first plunger is placed at a greater distance from the turntables and a semaphore 52 is provided near the crossings which is connected to the rack rods by a 40 suitable sprocket 53 and chain 54 or similar mechanism.

We claim:—

1. The combination with a plurality of intersecting railroad rails, of a casing formed 45 at each intersection, a grooved turntable arranged in each casing, a recessed shank depending from said turntable, a ball bearing arranged in said recessed shank, and means for rotating said turntable.

2. The combination with a plurality of intersecting railroad rails, of a casing formed at each intersection, a grooved turntable arranged in each casing, a hollow shank depending centrally from said turntable, a 50 post having a concave upper end extending from the bottom of said casing into the hollow portion of said shank, a ball arranged between the roof of said hollow portion and said post, and means for rotating said turntable.

3. The combination with a plurality of intersecting railroad rails, of a casing formed at each intersection, a grooved turntable arranged in each casing, a hollow shank depending centrally from said turntable, a ball 55

between the turntable and said casing arranged in said hollow portion, a plate secured to said shank, and means for rotating said turntable.

4. The combination with a plurality of intersecting railroad rails, of a casing formed at each intersection, a grooved turntable arranged in each casing, a hollow shank depending centrally from said turntable, a ball between the turntable and casing arranged in said hollow portion, a plate secured to the lower end of said shank and extending outward therefrom to the casing, said casing being provided with apertures adjacent the ends of said plate, and means for rotating said turntable.

5. The combination with a plurality of intersecting railroad rails, of a casing formed at each intersection, a grooved turntable arranged in each casing, a hollow shank depending centrally from said turntable, a ball in said hollow shank disposed between the turntable and the casing, a pinion secured to said turntable, a reciprocating rack rod engaging said pinion, a plunger adapted to be depressed arranged on one of said rails, a lever engaging said plunger; and a link secured to said rack rod and attached to the free end of said lever.

6. The combination with a plurality of intersecting railroad rails, of a casing formed at each intersection, a grooved turntable arranged in each casing, a hollow shank depending centrally from said turntable, a ball in said hollow shank disposed between the turntable and the casing, a pinion secured to said turntable, a reciprocating rack rod engaging said pinion, a plunger adapted to be depressed arranged on one of said rails, a projection on said plunger, a lever secured to said rail provided with a bifurcated end engaging said plunger projection, and a link connecting the other end of the lever with said rack rod.

7. The combination with a plurality of intersecting railroad rails, of a casing formed at each intersection, a turntable arranged in each casing, a pinion secured to each turntable, a rack rod engaging said pinion, means for moving said rack rod in opposite directions, and means connected to said rack rod for insuring the completion of the movement in either direction.

8. The combination with a plurality of intersecting railroad rails, of a casing formed at each intersection, a turntable arranged in each casing, a pinion secured to each turntable, a rack rod engaging said pinion, a lever pivoted to said rail and connected to said rod, a runway provided on the free end of said lever, a ball in said runway, and means for moving said rod.

9. The combination with a plurality of intersecting rails, of a casing formed at each intersection, a turntable arranged in each cas- 130

ing, a pinion secured to said turntable, a reciprocating rack rod engaging said pinion, a plunger adapted to be depressed disposed in an aperture in said rail, a lever engaging said plunger, a link connecting said rod and said lever, a second lever pivoted on said rail and connected to said link, a runway provided on the free end of said lever, and a ball in said runway.

In testimony whereof, we have hereunto set our hands at Oakland, California, this 31st day of October, 1914.

LUTHER SADLER.
ROBERT C. GECKLER.
